(57) **CLAIM**

The ornamental design for a sky roof rack, as shown and described.

DESCRIPTION

FIG. 1 is a left front perspective view of a sky roof rack for a vehicle according to the present invention.

FIG. 2 is a right rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a left front perspective view of the sky roof rack shown in FIG. 1, mounted alongside a lighter shaded sky roof rack that is not claimed in this application.

FIG. 9 is a rear view of the sky roof rack as shown in FIG. 8; and,

FIG. 10 is a top view of the sky roof rack as shown in FIGS. 8 and 9.

In FIGS. 8-10, the lighter shaded region is shown for environmental purposes only and forms no part of the present invention.
